UNITED STATES PATENT OFFICE.

HANS MICHELSEN, OF MINNEAPOLIS, MINNESOTA.

SHOE-SOLE-STITCHING MECHANISM.

1,369,458.

Specification of Letters Patent. Patented Feb. 22, 1921.

Application filed April 14, 1919. Serial No. 289,982.

To all whom it may concern:

Be it known that I, HANS MICHELSEN, a citizen of the United States, residing at Minneapolis, in the county of Hennepin and State of Minnesota, have invented certain new and useful Improvements in Shoe-Sole-Stitching Mechanism; and I do hereby declare the following to be a full, clear, and exact description of the invention, such as will enable others skilled in the art to which it appertains to make and use the same.

My invention relates to shoe sole stitching mechanism and is in the nature of an improvement on the "presser foot for sole stitching machines" disclosed in my prior Patent No. 989,511, of date April 11, 1911, and on the "sole stitching mechanism" disclosed and claimed in my prior Patent No. 1,083,373, of date January 6, 1914.

My present invention is in the nature of a presser foot and attachments therefor, whereby channels, to wit, either creases or grooves, may be cut in a shoe sole simultaneously with the stitching action and in a highly efficient manner.

Generally stated, the invention consists of the novel devices and combinations of devices hereinafter described and defined in the claims.

In the accompanying drawings which illustrate the invention, like characters indicate like parts throughout the several views.

Referring to the drawings:—

Figure 1 is a view in side elevation showing the invention applied to the presser foot bar of a sole stitching machine of any of the well known types;

Fig. 2 is a plan view of the parts shown in Fig. 1, some parts being sectioned;

Fig. 3 is a front elevation of the parts shown in Figs. 1 and 2, a two layer sole being shown in section on the stitching line;

Fig. 4 is a detail chiefly in section but partly in elevation showing the manner in which the presser foot toe is pivoted to the presser foot proper;

Fig. 5 is a plan view of the presser foot toe shown in Fig. 4;

Fig. 6 is a detail corresponding to Fig. 3, but showing portions of the attachment removed; and

Fig. 7 is a plan view showing a presser foot toe of hook-like form.

The character *a* indicates a two-layer shoe sole which is being stitched. Of the parts

of the machine, in so far as it is desirable for the purposes of this case to note the same, the numeral 8 indicates the fixed table or needle plate, the numeral 9 the vertically movable awl, the needle 10, and presser foot bar 11, which latter, as is well known, is given an intermediate vertical movement so as to permit the step-by-step feeding movement of the shoe sole under the action of the customary feeding mechanism. This vertically movable presser foot bar 11 carries my improved presser foot and the attachments thereto, as will now be noted.

The presser foot proper indicated by the numeral 12, at its upper portion, is in the form of a plate having perforations 12' therein, and it is rigidly but adjustably secured to the presser foot bar 11 by machine screws 13 passed through perforations in said bar, and through the perforations 12' and have their threaded ends screwed into a clamping plate 14. The perforations 12' are considerably larger in diameter than the screws 13 so that the said presser foot is capable of limited universal movements in the vertical plane in which it is fixed, this being important, as will presently appear. The presser foot toe 15 is swiveled to the lower portion of the presser foot 12 for limited oscillatory movements on horizontal axis so as to adapt itself to irregularities in the sole or to slightly tilted positions of the sole; and this pivotal connection is preferably made of a strong bolt screw 16, the head of which is countersunk into the foot 12 and the threaded end of which is screwed into the foot 15. The lower portion of this presser foot toe, of course, engages directly with the shoe sole. The toe shown in Fig. 95 7 is like that illustrated in the other views, except that it is provided with a hook-like end 15^a which is better adapted to close the creases after the stitching of the sole.

For forming a crease in the shoe sole for the stitches, I employ a knife, but for forming a groove, I employ a bar having a tubular groove cutter at its lower end. These two tools are herein broadly referred to as channel forming tools and the term "channel" is used in a sense broad enough to include either a crease cut by a knife or a groove cut out by a groove cutting tool.

The knife and the groove cutter may be interchangeably used and each comprises a rod or bolt-like body section 17 mounted for endwise movements on a line oblique to the

sole and in the vertical plane of the stitching line, in a so-called tool plate which, in fact, is a sort of supplemental adjustable part of the presser foot. This tool plate 18 is adjustably connected to the presser foot bar to screws 19 and 20. The screw 19 is screwed into the body of the presser foot 12 and works in a horizontal slot 21 of the tool plate 18, while the screw 20 is screwed into an arm 12^a of said presser foot and works in a horizontal groove 22 of said plate 18. The upper end of the arm 12^a has a rigid horizontally projecting screw-threaded stem 23. A nut 24 having a knurled head works on the stem 23 and has a swivel connection to a laterally projecting flange 18^a of the tool plate, so that by adjustments of the nut 24, the tool plate can be adjusted horizontally toward and from the awl 9 but without raising or lowering the said plate 18 and without changing its angle to the vertical plane of the stitching line.

The tool body 17, whether the knife or the groove cutting tool, is provided with knurled nut 25 that works on its threaded end and is confined in the notch cut in the tool plate 18 so that, by adjustments of the said nut 25, the tool may be raised and lowered. In the arrangement illustrated in Figs. 1 to 3, inclusive, the tool 17 is provided at its lower end with a crease cutting blade 17^a, while in the arrangement shown in Fig. 6, said tool is provided at its lower end with a tubular groove cutter 17^b.

At its intermediate portion, the tool 17 is preferably provided with a flattened portion 17^c adapted to be engaged by a set screw 26 threaded through one edge of the tool plate 18, to hold the tool securely in any adjustment in which it may be set and against rotation.

The adjustment of the entire presser foot attachment, permitted by the enlarged holes 12' is required to set the same properly in respect to the awl and the needle. The horizontal adjustment of the tool plate 18 permits setting of the knife or groove cutter always to proper distance ahead of the awl, regardless of the length of the stitches. It, of course, is understood that for sole stitching machines, it is customary to produce the feeding action of the sole by horizontal movements of the awl in the vertical plane of the stitching line. The vertical or ob-

lique adjustments of the knife or grooving tool are necessary in order to regulate the depth of the crease or the groove. Hence, as is evident, all of the required adjustments are provided for in an extremely simple and efficient way.

The efficiency of the invention herein disclosed and above described, has been thoroughly demonstrated in practice. In the use of the knife for forming a crease for the stitches, it is desirable to press down the walls of the crease so as to close the crease over the stitches and this will be automatically done when the hook-like presser foot toe, shown in Fig. 7, is used. When stitches are being made in grooves formed by the grooving tool, either form of presser foot toe may be used, but the form shown in Figs. 1 to 6, inclusive, will probably usually be employed.

What I claim is:

1. A presser foot attachment for shoe sole stitching machines, comprising a presser foot that is detachably securable to the presser foot bar of the machine, a tool plate rigidly secured to said foot with freedom for approximately horizontal forward and rearward adjustments, and a channel forming tool rigidly secured to said tool plate but adjustably to raise and lower said tool independently of the horizontal adjustment of said tool plate.

2. A presser foot attachment for shoe sole stitching machines, comprising a presser foot that is detachably securable to the presser foot bar of the machine, said foot having a laterally projecting vertical arm, a tool plate connected to said arm for approximately horizontal forward and rearward sliding movements, a nut and bolt connection between said arm and tool plate for adjusting the latter, a channel forming tool obliquely applied to said tool plate and depending from the same, and a nut and bolt connection between the plate and tool for vertically adjusting the latter independently of the adjustment of said tool plate.

In testimony whereof I affix my signature in presence of two witnesses.

HANS MICHELSEN
